UNITED STATES PATENT OFFICE

AZZEL C. BENNETT, OF HUDSON, NEW YORK, ASSIGNOR TO GIFFORD-WOOD COMPANY, OF HUDSON, NEW YORK, A CORPORATION OF NEW YORK

BUCKET FOR MATERIAL-HANDLING PLANTS

Original application filed October 21, 1926, Serial No. 63,938. Divided and this application filed March 13, 1929. Serial No. 346,590.

This invention relates generally to plants for handling semi-fluent materials such as coal, sand, gravel and the like, particularly of the type wherein the material is adapted to be conveyed from a pit to storage bins by means of a conveyor bucket.

Among other objects, the invention aims to provide means for guiding the bucket as it descends into the pit and also means to prevent the bucket from catching under the guides or tracks in the pit, when it is being hoisted.

This application is a division of my Patent No. 1,741,123, dated December 24, 1929.

15 In the drawings,

Fig. 1 is a side elevation of a hoist bucket embodying the invention; and

Fig. 2 is an end elevation of the same.

Referring particularly to the drawings, 20 there is shown a bucket 7 adapted to be lowered into a pit or into a space beneath a hopper (not shown) for receiving material such as coal, sand, gravel or the like from a gate, such as the one disclosed in the pending 25 Root application Serial No. 78,163 filed December 29, 1925. The bucket 7 is provided with co-operating jaws 11, and linkages 12 connect the jaws together, as disclosed in the parent application, to effect simultaneous 30 opening and closing. When the bucket is in proper position to be loaded, the gate is lowered by suitable mechanism which is manually operated by a hand wheel adjacent to the pit, as shown in the Root application 35 aforesaid. When the bucket is filled, it is hoisted out of the pit and conveyed to the point of storage by suitable hoisting and traversing units (not shown) located in the control house. The bucket is suspended and 40 elevated and lowered by means of a single line 15 passing around a sheave 16 on bail 17 which is pivoted to the bucket as at 18. Dumping is effected automatically upon descent of the bucket, and closing of the jaws takes place 45 upon descent of the bucket into the pit, as explained in the parent application.

In order to guide the bucket into proper position beneath the chute 15, two rollers 19 are journaled on each side of the bucket, the 50 pairs of rollers running in inclined double

tracks or guides 20, 21, secured to each side wall of the pit and extending nearly to the bottom of the pit and spaced apart sufficiently to permit the rollers to pass between them. The rollers are so arranged that when they engage the double guides, the top of the bucket is level. As there are two rollers on each side of the bucket, tilting of the bucket is prevented so long as the double guides are engaged by the rollers. At their lower portions, the tracks 20 and 21 are parallel and near the mouth of the pit, the upper tracks diverge upwardly and the lower tracks are continued above the level of the ground. This arrangement is, however, merely illustrative. For a more complete disclosure of an illustrative material handling plant with which the invention may be used, see Fig. 1 of the Cook application, Ser. No. 312,150, and Fig. 1 of the Towne application, Ser. No. 146,890.

When the trolley is stopped over the pit (or over a bin), the momentum of the bucket will cause it to swing like a pendulum. The length of the pendulum and hence the length 75 of the arc traversed necessarily increases as the bucket is lowered. Therefore, the bucket cannot be lowered unless the swinging motion practically ceases. However, due to the wind and other causes, the bucket may continue to swing and twist slightly, and thus a considerable time may be lost before the bucket is in position to be lowered into the pit and is substantially motionless. In order to save time, guide means are provided on the bucket to direct it into the mouth of the pit even though the bucket may be swinging 80 slightly horizontally or vertically.

Secured to each side of each jaw is a guide shoe 25 which preferably extends from a point just below the jaw pivot downwardly below the bottom of the bucket. These shoes may be in the form of angle bars, as shown, thus stiffening and protecting the jaws, and have one of their flanges projecting outwardly beyond the side of the bucket. The lower ends of the shoes are tapered as shown at 26, so that when the bucket is lowered into the mouth of the pit, the tapered ends 26 strike first the side walls of the pit and then the 95 100

tracks 20, thus keeping the bucket away from the walls of the pit and directing the rollers onto the tracks. The shoes 25 serve not only to guide the bucket into the pit, but also to strengthen the jaws and prevent the jaw operating mechanism of the bucket itself from being injured by such battering as it is subjected to in ordinary usage.

As shown in Fig. 1, additional guide shoes 10 27 are provided which are rigidly secured to the sides of the bucket at their rear upper ends. These shoes 27, which may also be of angle bars, extend upwardly above the top of the bucket and have their upper ends 15 tapered, as shown. The shoes 27 direct the upper rollers onto the guides 20 when the bucket is lowered and also prevent any part of the bucket from catching under the tracks 20 when the bucket is raised. When the 20 loaded bucket is hoisted to a point clear of the upper tracks 21, it may then be momentarily clear of both tracks. As soon as the rollers leave the tracks, the bucket is free to swing, by gravity, to a point more nearly 25 directly beneath the trolley, and the upper ends of the rear shoes 25 or part of jaw operating mechanism might catch beneath the tracks 20, particularly if the bucket turns axially, thus preventing the bucket from being hoisted. This catching or fouling of the 30 bucket is prevented, however, by the shoes 27 which strike the sides of tracks 20 before the bucket catches under said tracks. Also, if the bucket is hoisted too rapidly, the tendency of the rollers is to engage the tracks 21 instead of the tracks 20. Then when the 35 bucket clears the tracks 21, it may swing to a point more nearly under the trolley, and being suddenly out of engagement with both 40 tracks may twist so that one of the rollers would pass behind the track 20. This will be prevented, however, by the shoe 27 on the opposite side of the bucket striking the adjacent track and thus straightening the bucket 45 so that all of the rollers will engage the tracks properly.

Obviously, the present invention is not restricted to the particular embodiment thereof herein shown and described.

50 What I claim is:—

1. A plant for handling semi-fluent materials comprising, in combination, a support; a hoist bucket; upwardly inclined guides for the bucket; said guides including upper and 55 lower guides for a portion of the path of movement of the bucket, and the upper guide terminating short of the point where the lower guide terminates, so that the bucket may be hoisted free of the guides; rollers on the 60 opposite sides of the bucket for entering between said guides; and means secured at the top of the bucket to prevent one of the rollers from catching under one of the lower guides when the bucket is being hoisted.

65 2. The combination of a hoist bucket and a

pit having inclined bucket guides, characterized by the employment of upwardly and downwardly projecting members fixed to the sides of the bucket, said projecting members preventing the bucket from catching under the guides during ascent and also turning the bucket angularly about a vertical axis during descent so as properly to engage the guides.

70 3. A hoist bucket adapted to be operated in conjunction with bucket tracks which are inclined relative to the vertical, comprising, in combination, a body; means on the body for operative engagement with the bucket tracks; and guide shoes on the body projecting upwardly above the top thereof and laterally outwardly to turn the bucket, during hoisting, to assume the proper position relative to the tracks.

75 4. A hoist bucket adapted to be lowered into a loading pit comprising pivoted jaws for dumping the contents of the bucket; and means rigidly secured to the jaws and projecting downwardly and laterally outwardly therefrom to guide the bucket as it moves in the pit.

80 5. A hoist bucket adapted to be moved into and out of engagement with bucket tracks, and having means fast to the bucket on opposite sides and extending upwardly above the top thereof and downwardly below the bottom of the bucket to guide the bucket into and out of engagement with said bucket tracks.

85 6. In combination with a hoist bucket of the character described adapted to roll on an inclined trackway; means to lower and raise the bucket into and out of engagement with the trackway; and means on the bucket rigidly fixed to the sides thereof so as to be engageable with the trackway to guide the bucket into and out of engagement with the trackway.

90 7. In combination with an inclined trackway, a hoist bucket having means thereon to roll on the trackway; means to lower the bucket into engagement with the trackway and also to hoist the bucket free of the trackway rigidly fixed to and carried at opposite sides of the bucket and projecting below the bottom thereof to engage the tracks and guide the bucket onto the trackway when the bucket is lowered.

95 8. In combination, an inclined trackway; a hoist bucket adapted to roll on the inclined trackway and be raised clear thereof; means secured to and extending above the bucket at each side thereof to prevent the bucket from catching beneath the trackway when the bucket is being hoisted.

100 9. A hoist bucket comprising, in combination, a body portion; jaws for closing the bottom of the bucket and having side walls pivoted to the sides of the bucket; means connecting the jaws so that they open and close simultaneously; and angle bars secured to the side walls of the jaws to strengthen the same

and to prevent the jaw connecting means and the sides of the jaws from being battered.

10. In a hoist bucket adapted to be lowered into engagement with inclined tracks; jaws for closing the bottom of the bucket and having side walls pivoted to the sides of the bucket; and means secured to the side walls of the jaws to strengthen and protect the same from battering; said means extending below the bottom of the bucket to guide the bucket in proper engagement with the tracks.

11. A bottom dumping conveyor bucket comprising, in combination, a body; a pair of jaws pivoted on the body and together closing the bottom of the bucket; and an angle bar secured to each jaw at each side of the bucket to strengthen the jaw and protect the bucket; said angle bar extending below the bottom of the jaw, so that the bucket has two downwardly projecting parts on each side thereof to guide it in its descent.

12. A bottom dumping conveyor bucket comprising, in combination, a body; a pair of jaws pivoted on the body and together closing the bottom of the bucket; an angle bar secured to each side of the bucket and projecting a short distance above the top thereof to obviate fouling of the bucket during hoisting; and an angle bar secured to each jaw at each side of the bucket to strengthen the jaw and protect the bucket; said last-mentioned angle bar extending below the bottoms of the jaws, so that the bucket has two downwardly projecting parts on each side thereof to guide it in its descent.

In testimony that I claim the foregoing as my own, I have hereto affixed my signature.

CERTIFICATE OF CORRECTION.

Patent No. 1,791,882.

Granted February 10, 1931, to

AZZEL C. BENNETT.

It is hereby certified that error appears in the above numbered patent requiring correction as follows: In the heading to the printed specification and drawing, date of original application, for "October 21, 1926" read October 21, 1925; and that the said Letters Patent should be read with this correction therein that the same may conform to the record of the case in the Patent Office.

Signed and sealed this 10th day of March, A. D. 1931.

M. J. Moore,
Acting Commissioner of Patents.
